FIG. 4

UNITED STATES PATENT OFFICE

164,924

CONTAINER FOR DOLL

Lester F. Hinz, Los Gatos, Calif.

Application December 6, 1949, Serial No. 6,443

Term of patent 14 years

(Cl. D58—8)

To all whom it may concern:

Be it known that I, Lester F. Hinz, a citizen of the United States, residing at Los Gatos, county of Santa Clara, State of California, have invented a new, original, and ornamental Design for Container for Doll, of which the following is a specification, reference being had to the accompanying drawing, forming a part hereof.

Fig. 1 is a top plan view of a container for a doll, showing my new design;

Fig. 2 is a side elevation;

Fig. 3 is a front elevation; and

Fig. 4 is a bottom plan view.

I claim:

The ornamental design for a container for doll, as shown.

LESTER F. HINZ.
